No. 718,963.

PATENTED JAN. 20, 1903.

J. W. FARR.

SHINGLING BRACKET.

APPLICATION FILED JULY 23, 1902.

NO MODEL.

UNITED STATES PATENT OFFICE.

JOHN W. FARR, OF MARION, INDIANA, ASSIGNOR OF ONE-HALF TO
SAMUEL H. DAVIS, OF MARION, INDIANA.

SHINGLING-BRACKET.

SPECIFICATION forming part of Letters Patent No. 718,963, dated January 20, 1903.

Application filed July 23, 1902. Serial No. 116,686. (No model.)

To all whom it may concern:

Be it known that I, JOHN W. FARR, a citizen of the United States, residing at Marion, in the county of Grant and State of Indiana, 5 have invented a new and useful Shingling-Bracket, of which the following is a specification.

This invention relates to devices employed more particularly for the purpose of supporting the workmen and their supplies upon roofs while attaching shingles thereto, but which may be adapted for use in other localities and for other purposes.

The object of the invention is to produce a 15 device simple in construction, easily and readily applied, and in which the supporting means for the weight is caused to lock the device in position when applied and which will require no outside means to enable the 20 device to be attached to the roof or other part of a structure.

The invention consists in certain novel features of construction, as hereinafter shown and described, and specified in the claims.

25 In the drawings illustrative of the invention, Figure 1 is a perspective view of the device complete. Fig. 2 is a side elevation, partially in section.

Devices of this character are usually designated as "shingling-brackets" and are employed upon roofs while attaching shingles thereto and disposed at suitable intervals to support the footboards for the feet of the workmen and also to assist in supporting the 35 supplies of shingles and other material and tools. The device may also be employed with slight modifications for the purpose of securing staging upon the sides of buildings and in many other localities, and I do not, therefore, 40 wish to be limited in the use of the device to any particular locality or for any particular purpose and reserve the right to employ the device for any purpose and in any locality to which it is applicable.

45 The device consists in a base-plate 10, having an offset 11 to cause the base to conform to the shingles applied to the roof and with its upper end 12 formed comparatively thin and in elongated wedge shape, so that it may 50 be inserted for a considerable distance beneath the butt-ends of the shingles already

attached to the roof. In attaching the plate the upper end 12 will preferably be forced beneath the upper row of the shingles, while the offset 11 will rest in engagement with the 55 butt-end of the next lower row of shingles, as shown in Fig. 2, wherein one of the shingles of the uppermost row is represented at 13, one of the butt-ends of the next row at 14, and one of the shingles of the next row at 15. 60

In operation these brackets are applied to the uppermost row of shingles, and then when the shingles have been applied as far as the workmen can reach, generally three or four feet upward on the roof, the brackets 65 are detached and moved upward and again engaged with the uppermost row, and so on until the roof is complete.

The base 10 is provided with a longitudinal slot, (indicated at 16,) and within this slot 70 a lever 17 is movably supported and pivotally connected at 18 between ears 19, the ears extending upward at the sides of the slot 16 from the base 10, as shown. The upper end of the lever 17 is provided with a transverse 75 plate 20, preferably formed integral therewith and adapted to engage the outer surface of the shingle beneath which the end 12 of the lever 17 has been projected, as indicated in Fig. 2. The lever 17 is formed with an 80 offset 29, extending downward into the slot 16, and with its outer upper face inclined, as shown at 27.

The plate 20 will be equal in width to the plate 10 and will register with the flattened 85 end 12, as indicated in Fig. 1, the two parts 12 20 thus forming comparatively broad jaws, engaging opposite sides of the shingle 13.

The plate 20 is provided with one or more spurs 22, extending downward and adapted 90 to engage the upper surface of the shingle 13, and thereby insure the proper "grip" between the parts, and the lower end of the plate 10 will likewise be provided with one or more spurs 23, adapted to engage the shingle 95 15 to still further increase the grip of the device.

Attached flexibly by one end to the upper end of the plate 20 and by the other end to the lower end of the plate 10 is a supporting- 100 bracket formed of two arms 24 25, the shorter arm 24 connected by ears 26 and pivot 30 to

- the plate 20 and the longer arm 25 similarly connected by ears 28 and pivot 31 to the plate 10, as shown. The arm 24 is forked at its outer end and adapted to embrace the arm 25 a short distance down from its upper end, whereby an extension 32 is formed to retain the platform or foot-bar in place, as herein-after explained. The two portions 24 25 are united by a pivot 33, so that a slight degree of play is permitted between the parts 24 25. The pivots 30 31 likewise afford a slight degree of movement between the lower ends of the arms 24 25 and the lever 17 and the base 10, respectively, so that when attaching and 15 detaching the device the requisite movement of the lever 17 will be permitted. The lever 17 thus possesses the requisite degree of flexibility to enable it to perform its work, while at the same time the load-supporting members 24 25 have a toggle action and will exert their force to maintain the lever and base-plate in positive and firm engagement with the shingles, as will be understood, the weight placed on the arms 24 and 25 causing the clamping member 20 of the lever 17 and the lower end of the base-plate to firmly engage and clamp the supporting-surface. It will be noted by this arrangement that when the device is to be applied the depression 30 of the lower end of the lever 17 will cause it to engage the supporting-surface and act as a fulcrum, so that the clamping member 20, attached to the upper end thereof, will be moved away from the end 12 of the base-plate 35 10, whereby the end 12 may be slid under the shingle 13 until the shoulder 21 engages its lower or butt end. When the bracket is to be removed, this depression of the lower end of the lever 17 into contact with the supporting-surface causes the clamping-jaws to open and release the device from the shingle. It also causes the lower end of the plate 10 to move upward out of engagement with the supporting-surface.
- 40 In applying the bracket after the end 12 has been slid under the shingle, as 13, the lever 17 is released and the bracket-arms forced against the plate 20 and the lower end of the plate 10, which will cause the plate 20 to engage the outer surface of the shingle 13 and project the spur 22 therein and also project the spur 23 on the plate 10 into the shingle 15, and thus complete the coupling between the parts.
- 45 When it is desired to detach the bracket, it is necessary only to grasp one of the arms 24 or 25 and pull slightly thereon, which causes the end of the lever 17 in the slot 16 to project therethrough and engage the supporting-surface beneath it, thereby causing its opposite end carrying the plate 20, which forms the movable jaw of the clamp, to open and become disengaged from the shingle 13. In this position the end of the lever 17 acts as the fulcrum, the entire bracket being the lever acting on said fulcrum, and the pulling exerted on the arms also causes the lower end of

the plate 10, carrying the spur 23, to move upward out of contact with the supporting-surface in the form of the shingle 15, and the 70 bracket may then be readily slipped out and moved to another place. It will thus be seen that no screws or similar devices are necessary to the operation of the device.

These devices will be arranged at as frequent intervals as required to properly support the platform, which will rest across the arms 24 and be held in place by the projections 32. These platforms are generally sections of scantling of suitable length, and the 80 brackets will be located at the proper distances longitudinally of the roof to insure a safe support for these scantlings, with which the feet of the workmen engage while attaching the shingles. 85

By the construction of this device it will be obvious that the weight applied to the portion 24 25 will exert a strong downward force upon the plate 20 and firmly grip the parts 20 and 12 upon the shingle 13 and also firmly 90 force the lower end of the plate 10 into engagement with the shingle 15, and any increase of weight will serve to increase the grip between the parts, so that the greater the weight and pressure brought to bear 95 against the scantling or other platform the greater, correspondingly, will be the "hold" of the device upon the roof and the tendency to slip or release its hold correspondingly decreased. The chances for the failure of the 100 device to perform its work are therefore extremely remote and the safety and efficiency correspondingly increased.

The whole device is extremely simple and consists of few parts, and therefore not liable 105 to become disarranged.

The different parts of the device will be constructed, preferably, of malleable iron, and the parts will be proportioned to withstand the strains and pressure to which they will be 110 subjected.

The device may be of any size and the proportions changed and modified to adapt the device to the various purposes for which it may be employed. 115

The device may be employed under certain conditions and with slight modifications to support staging or other structures upon the sides of buildings by adapting the parts 12 and 20 to engage the clapboards or siding instead of shingles, as will be readily understood.

The device might also be employed with slight modifications for supporting the workmen while attaching slates or tiles to roofs, 125 building chimneys, and attaching cresting and other ornaments, or in repairing roofs; but these modifications would not be a departure from the principle of the invention or sacrifice any of its advantages. 130

Having thus described my invention, what I claim is—

1. A shingling-bracket comprising a base-plate and a lever pivotally connected at an

intermediate point, provided at their upper ends with shingle-engaging clamp members and adapted at their lower ends for alternate contact with a supporting-surface, the base-
5 plate being provided at its lower end with shingle-engaging means, and pivotally-connected bracket-arms having their remote extremities connected respectively with the clamp member of the lever and with the lower
10 end of the base-plate.

2. A shingling-bracket comprising a base-plate having a longitudinal slot therein, a lever pivotally connected at an intermediate point to said base-plate and having its upper
15 end spaced therefrom and provided with a shingle-engaging spur and the other end mov-
ably disposed in said slot and adapted to ex-
tend therethrough, and connected bracket-
arms having their extremities connected to
20 the upper end of the lever and to the lower
end of said base-plate respectively.

3. A shingling-bracket comprising a base-plate having a shingle-engaging clamp mem-

ber at its upper end to engage the under side of a row of shingles and with an offset adapted 25 to engage the butt-ends of the next lower row of shingles, a lever pivotally supported upon said base-plate and having at its upper end a shingle-engaging clamp member adapted to engage the outer surface of the shingle en- 30 gaged by the clamp member of the base-plate, the other end of said lever being offset to correspond with the offset of said base-plate, said offset end of said lever being adapted for contact with a supporting-surface, and connected 35 bracket-arms coupled respectively to the clamp member of said lever and to the lower end of said base-plate.

In testimony that I claim the foregoing as my own I have hereto affixed my signature in 40 the presence of two witnesses.

JOHN W. FARR.
